Primary Examiner—Jeffrey Asch*Attorney, Agent, or Firm*—Vernon C. Maine[57] **CLAIM**

The ornamental design for a pump tip for a soap dispenser, as shown and described.

DESCRIPTION

FIG. 1 is a perspective view of the pump tip for a soap dispenser showing my new design;

FIG. 2 is a top view thereof;

FIG. 3 is a side elevation thereof;

FIG. 4 is a front elevation thereof, the broken line depiction of a pump hose being for illustrative purposes only and forming no part of the claimed design; and,

FIG. 5 is a bottom view thereof.
